UNITED STATES PATENT OFFICE.

JOHN QUIST AND CHARLES QUIST, OF MYSTIC, IOWA, ASSIGNEES OF ONE-HALF TO O. P. PEARSON AND CHARLES L. BERRY, OF MYSTIC, IOWA.

MECHANICAL MOVEMENT.

SPECIFICATION forming part of Letters Patent No. 703,825, dated July 1, 1902.

Application filed November 18, 1901. Serial No. 82,752. (No model.)

To all whom it may concern:

Be it known that we, JOHN QUIST and CHARLES QUIST, citizens of the United States, residing at Mystic, in the county of Appanoose and State of Iowa, have invented certain new and useful Improvements in Mechanical Movements; and we do declare the following to be a full, clear, and exact description of the invention, such as will enable others skilled in the art to which it appertains to make and use the same.

This invention relates to a novel mechanical movement; and the object of the invention is to provide simple and improved mechanism applicable to washing-machines, churns, and to all other machines in which it is desired to obtain an oscillatory motion of one shaft or pivoted part from a rotating shaft whose axis is at right angles to the axis of the shaft or pivoted part first mentioned.

The invention is illustrated in the accompanying drawings, in which we have shown it in connection with a washing-machine, and wherein—

25 Figure 1 is a vertical sectional view of a washing-machine embodying the invention. Fig. 2 is a top plan view of the gearing. Fig. 3 is an end elevation of the gearing, showing the yoke at right angles to the rotating shaft. 30 Fig. 4 is a detail view of the yoke, and Fig. 5 is a detail view of the grooved ball or head.

Referring now more particularly to the drawings, the numeral 1 designates a washing-machine of any approved construction, 2 its oscillatory shaft carrying a rubber 3, and 35 4 an operating-shaft journaled in a bearing-bracket 5 and carrying a fly-wheel 6 and crank-handle 7 whereby it may be operated.

The invention consists in means for transmitting oscillatory motion to the shaft 2 from the continuously-rotating shaft 4, whose axis is arranged at right angles to said oscillatory shaft.

45 Fixed to the upper end of the oscillatory shaft and journaled at 8 to the bearing-bracket to swing in a horizontal plane is a yoke 9, carrying a swiveled shoe 10, which traverses a groove 11, formed in a ball or spherical head fixed to the inner end of the 50 rotating shaft 4. This groove is of a peculiar form, having substantially the shape of the

figure 8, and the shoe in traversing it is caused to impart oscillatory motion to the yoke and thence to the shaft 2.

In the operation of the device, when motion 55 is imparted to the rotating shaft, with the parts arranged as in Fig. 3, the shoe, which is located at the point of crossing of the two loop-shaped portions of the groove, is caused to first follow the cross of one of the 60 said loop-shaped portions, whereby the yoke is swung in one direction of its oscillation, and then follow the cross of the other loop-shaped portion of the groove, whereby the yoke is caused to swing in a direction reverse 65 to that previously described.

From the foregoing description, taken in connection with the accompanying drawings, the construction, mode of operation, and advantages of the invention will be readily understood without a more extended explanation.

Various changes in the form, proportion, and minor details of construction may be made within the scope of the invention without departing from the spirit or sacrificing 75 any of the advantages thereof.

As before stated, the invention is applicable to the shuttle motion of sewing-machines, to churns, to washing-machines, and to all 80 machines in which it is desired to obtain an oscillating motion of one shaft or pivoted part from a rotating shaft arranged at right angles thereto. Hence we do not limit the invention in application to a washing-machine 85 or any other particular structure, but reserve the right to employ it wherever it may be found applicable.

Having thus described our invention, what we desire and claim by Letters Patent is— 90

1. A mechanical movement embodying an oscillatory shaft, a rotating shaft, the axes of the shafts being arranged at right angles to each other, a swinging yoke connected to the oscillatory shaft, a ball or spherical head connected to the rotating shaft and having a substantially 8-shaped groove, and a shoe upon the yoke to traverse said groove, whereby oscillatory motion is imparted to the said oscillatory shaft and yoke, substantially as 95 described.
2. The combination with a suitable bear-

ing, an oscillatory shaft, and a rotating shaft journalized in said shaft being disposed at right angles to each other, of a yoke fixed to the oscillating shaft and mounted to swing upon said bearing, a ball or spherical head carried by the rotating shaft and having a substantially 8-shaped groove, and a swiveled shoe upon the yoke traversing said groove, substantially as described.

In testimony whereof we have hereunto set our hands in presence of two subscribing witnesses.

JOHN QUIST.
CHAS. QUIST.
